HULL

William O. Doty, 406 Smedeker Ave., Jerseyville, Ill.

Filed Dec. 9, 1965, Ser. No. 132

Term of patent 14 years

(Cl. D71—1)

FIG.1

FIG.2

FIG.3

FIG.4

FIG.5

FIG.6

FIG. 1 is a bottom plan view of a hull, showing my new design,

FIG. 2 is a side elevational view thereof,

FIG. 3 is a side elevational view thereof of the side opposite to that shown in FIG. 2,

FIG. 4 is a front elevational view thereof,

FIG. 5 is a rear elevational view thereof, and

FIG. 6 is a top plan view thereof.

The portions shown in broken lines in FIG. 2 are included for illustrative purposes only.

I claim:

The ornamental design for a hull, substantially as shown and described.
